(57) **CLAIM**

The ornamental design for a display panel or screen with computer generated image of the body pressure distribution pattern for seat cushion support layer, as shown and described.

DESCRIPTION

The FIGURE is a front elevational view of the display panel or screen with computer generated image of the body pressure distribution pattern for seat cushion support layer in accordance with an embodiment of the present invention.

The broken line showing of the display panel or screen is for the purpose of illustrating environmental structure and form no part of the claimed design.
